Specification for Design.

Patented Aug. 10, 1920.

Application filed November 6, 1919. Serial No. 336,221. Term of patent 14 years.

To all whom it may concern:

Be it known that I, WILLIAM J. NEWTON, a citizen of the United States, residing at Bridgeport, county of Fairfield, State of Connecticut, have invented a new, original, and ornamental Design for Double-Toggle Switch-Plates, of which the following is a specification, reference being had to the accompanying drawings, forming a part thereof.

In the drawing, Figure 1 is a plan view of a double toggle switch plate showing my novel design;

Fig. 2 is a sectional view taken on the line 2—2 in Fig. 1, looking in the direction of the arrows, and

Fig. 3 is a sectional view taken on the line 3—3 in Fig. 1, looking in the direction of the arrows.

What I claim is—

An ornamental design for a double toggle switch plate, as shown.

WILLIAM J. NEWTON.
